UNITED STATES PATENT OFFICE.

ISAAC LEFKOWITZ, OF NEW YORK, N. Y.

WAIST.

1,021,415.

Specification of Letters Patent. Patented Mar. 26, 1912.

Application filed July 7, 1911. Serial No. 637,319.

To all whom it may concern:

Be it known that I, ISAAC LEFKOWITZ, a citizen of the United States, and a resident of the borough of Manhattan, county, city, 5 and State of New York, have invented certain new and useful Improvements in Waists, set forth in the following specification.

This invention relates to a combination 10 garment and its embodiment is shown as a lady's waist combining in addition to the waist proper, a girdle and a sash.

An object of the invention is to facilitate 15 and simplify the operation of dressing without a consequent sacrifice in general appearance and style. In fact it is rather an object of the invention to increase the stylishness and appearance of neatness in the wearer.

A still further object of the invention is 20 to provide a lady's waist having a solid back and parted lapping sections at the front so arranged that they are self-adaptable to various bust measures without any alterations in the waist and so that the entire 25 waist may be donned and secured to the wearer without the use of pins, hooks or buttons.

An illustrative embodiment of the invention 30 is described in detail in the following specification and shown in the accompanying drawings, which form a part of this application, in which like characters designate corresponding parts and in which,—

Figure 1 is a front elevation of the waist 35 held in position with the sash strips crossing and pendant; Fig. 2 is a rear elevation of the waist as shown in Fig. 1; Fig. 3 is a front elevation of the waist as it would appear applied to the wearer; Fig. 4 is a 40 rear elevation of the structure of Fig. 3; and Fig. 5 is a pattern illustrating a gore combining a waist section, a girdle section and a sash section.

The waist illustrated is provided with a 45 solid back portion 1 of any suitable pattern, and on which are provided suitable arm holes and the usual neck opening. In the embodiment illustrated the solid portion of the waist is the back 1 which has the short 50 waist-skirt 3 to be secured to the wearer as by the skirt band of the skirt 4. As a further aid in holding in place this solid portion 1 it may be secured by the belt tape 5, shown suitably stitched to the lower margin 55 of the solid portion 1 of the waist.

The body portion of the waist opposite

the solid portion is completed by two lapping sections 6 and 7, which also combine other parts as will presently appear. These sections may, of course, be patterned and 60 shaped so as to conform to the body contour and size of the wearer. The portion 7^b shows a satisfactory pattern for the left front body section.

7^b indicates the shoulder seam; 7^a the arm 65 seam; 7^m the side seam; and 7^l the lap edge which is overlapped by the corresponding ornamented edge 6^l of the right hand section 6 and so as to form a closure for the garment.

The portion 7^b of the pattern shown in Fig. 5 has a terminal edge 7^w cut to conform to the waist line as indicated particularly in Fig. 3. The waist section 7^b continues into the girdle section 7^g, which in turn is 75 continued into the sash 7^s. The pattern for the right side 6 is precisely similar to the pattern for the left side 7. In fact both sections are cut to the same pattern, the goods being folded.

As soon as the wearer has donned the garment to the extent of thrusting the arms through the sleeves 2, the tape 5 should be secured about the waist of the wearer by fastening the ends of the same together in 85 any suitable manner as by a knot. The skirt 4 is then secured in the usual manner with its band overlying the waist-skirt 3. The pendant sash portions 6^s and 7^s are 90 then crossed as shown in Fig. 1 and are drawn outwardly about the waist of the wearer so that the edges 6^w and 7^w are a neat terminal edge for the waist overlying the skirt 4 and so that the girdle portions 6^g and 7^g crush and drape themselves 95 about the waist of the wearer in the form of a neat crush-girdle, the ends of which are knotted in any suitable manner and position as at the side or back into a knot 8. The ends are allowed to depend in any desired manner to simulate a sash or panel.

The neck opening is shown fitted with a collar comprising two separate similar portions 9 and 10 which respectively terminate, over the solid part 1 of the waist, in two pendant triangular shaped portions 9^p and 10^p which overlap each other as shown. These collar portions 9 and 10 are attached to the waist opening only along the edges 11 and 12. By this construction the waist 105 readily adapts itself to various bust measures and contours, it being merely neces-

sary to draw up the girdle to the desired tightness while the front sections 6^b and 7^b drape themselves over the bust contour of the wearer and at the same time the lapping sections 9^p and 10^p of the collar shift over one another to insure the proper "set" for the collar.

The waist may be made up in any desired fabric preferably of light weight however.

10 Although a blouse waist of a peculiar and ornamental design embodied particularly in the contour of the lapping edges of the front sections; the cut of the girdle sections; and the sash sections is shown in the drawings 15 illustrating the embodiment of this invention, the said ornamental design forms no part of the present mechanical invention, but is intended to be covered by my application Serial No. 637,361, filed on even date 20 herewith.

What is claimed and what is desired to be secured by United States Letters Patent is:—

1. A blouse-waist forming a finished outer 25 garment comprising a body-fitting back, solid from neck to waist-line; separate, symmetrical, lapping front sections joined to said back and each depending from the shoulder to drape the bust and each having 30 a lower terminal edge conforming to the waist-line when said sections are lapped over one another and continuing forward from the waist-line of said back to mid-front position; broad, crushable, girdle-sections, each continuing from a said front section and each adapted to overlie and conceal 35 the lower terminal edge of the opposite front section; and means for securing together said girdle-sections about the waist 40 of the wearer.

2. A blouse-waist forming a finished outer garment comprising a body-fitting back, solid from neck to waist-line; separate, symmetrical, lapping front sections 45 joined to said back and each depending from the shoulder to drape the bust and each having a lower terminal edge conforming to the waist-line when said sections are lapped over one another and continuing forward 50 from the waist-line of said back to mid-front position; broad, crushable, girdle-sections, each continuing from a said front section and each adapted to overlie and con-

ceal the lower terminal edge of the opposite front section; and sash-sections, each continuing from a girdle-section to be tied together to secure the garment and add finish thereto.

3. A blouse-waist forming a finished outer garment comprising a body-fitting back, solid from neck to waist-line; a tuck-in skirt depending from said solid back to be gripped by the wearer's skirt-band; separate, symmetrical, lapping front sections joined to said back and each depending from the shoulder to drape the bust and each having a lower terminal edge conforming to the waist-line when said sections are lapped over one another and continuing forward from the waist-line of said back to mid-front position; broad, crushable, girdle-sections, each continuing from a said front section and each adapted to overlie and conceal 60 the lower terminal edge of the opposite front section; and means for securing together said girdle-sections about the waist 65 of the wearer.

4. A blouse-waist forming a finished outer garment comprising a body-fitting back, solid from neck to waist-line; a tuck-in skirt depending from said solid back to be gripped by the wearer's skirt-band; a tie-tape, secured at the waist-line to said back to tie at the front about the waist of the wearer; separate, symmetrical, lapping front sections joined to said back and each depending from the shoulder to drape the bust and each having a lower terminal edge conforming to the waist-line when said sections are lapped over one another and continuing forward from the waist-line of said back to mid-front position; broad, crushable, girdle-sections, each continuing from a said front section and each adapted to overlie and conceal 70 the lower terminal edge of the opposite front section; and means for securing together said girdle-sections about the waist 75 of the wearer.

In witness whereof, I have signed my name to this specification, in the presence 80 of two subscribing witnesses.

ISAAC LEFKOWITZ.
